Patented Aug. 31, 1920.

2 SHEETS—SHEET 2.

UNITED STATES PATENT OFFICE.

THOMAS S. CATLIN, OF INDIANAPOLIS, INDIANA.

CONTAINER.

1,351,325.

Specification of Letters Patent. Patented Aug. 31, 1920.

Application filed January 9, 1917. Serial No. 141,372.

To all whom it may concern:

Be it known that I, THOMAS S. CATLIN, a citizen of the United States, residing at Indianapolis, in the county of Marion and State of Indiana, have invented certain new and useful Improvements in Containers; and I do hereby declare the following to be a full, clear, and exact description of the invention, such as will enable others skilled in the art to which it appertains to make and use the same.

This invention relates to improvements in containers, and more particularly to such as are especially adapted for use during the operation of milking or other like operations, where there is the possibility of accidental over-turning of the container, and where it is desirable to prevent such an accident from causing loss of the contained substance.

An object in view is the provision of a cover or closure for a container adapted to permit the inflowing of liquid and to prevent its discharge, and a further object is the provision of means for preventing accidental removal or dislocation of such closure from the receptacle.

With these and further objects in view, as will in part hereinafter become apparent and in part be stated, the invention comprises certain novel constructions, combinations and arrangements of parts as subsequently specified and claimed.

In the accompanying drawings,—

Figure 1 is a sectionl elevation of a container embodying the features of the present invention.

Fig. 2 is a top plan view thereof.

Fig. 3 is an enlarged, detail, fragmentary side elevation of one of the ears of the receptacle, a fragment of the bail being seen partly in elevation and partly in cross section.

Fig. 4 is a vertical, central section taken on the plane indicated by line 4—4 of Fig. 3.

Fig. 5 is an enlarged, detail, perspective view of a fragment of the bail detached.

Figs. 6, 7 and 8 are views, respectively, similar to views 3, 4 and 5 of a slightly modified embodiment of the invention.

Referring to the drawing by numerals, 1 indicates a bucket or other appropriate container, having a cover or closure 2 provided with an annular outstanding flange 3 adapted in operation to rest upon an annular bead 4 formed at the upper edge of the bucket.

A pendent annular flange 5 extends from the closure 2 downward from flange 3 and is adapted to snugly fit within the upper portion of the container 1. The closure 2 is 60 preferably formed of an upwardly tapering body rising from the flange 3 for a distance sufficient for accommodating a funnel-like portion 6 depending from the upper part of the inclined walls of the closure 2 without 65 having the funnel 6 extending an objectionable distance into the bucket or container 1. The upper edge of the funnel 6 is formed integral with the upper edge portion of the inclined walls of closure 2, so that the funnel 6 in fact forms a part of the closure 2. The lower portion of the funnel 6 terminates 70 in a cylindrical throat 7, formed with an annular bead 8, on which rests an annulus 9 within the throat 7. The annulus 9 carries 75 a fine, preferably metallic, screen 10. A cap 11 rests upon the annulus 9 for holding the same in place, the said cap consisting of a cylindrical member preferably formed of sheet metal and snugly fitting in the upper 80 portion of the throat 7, the upper end of the cylindrical portion being closed by a wire mesh screen 11', preferably of larger gage than the mesh of the filter 10. As a further precaution for avoiding entrance of foreign 85 substances through the throat 7, a filter fabric 12 is preferably stretched across the annulus 9 before the same is introduced into the throat 7, so that the fabric 12 will be clamped 90 between the annulus and the bead 8. An operating handle 13 is formed on the cap 11, so that the cap may be easily applied and as 90 easily removed.

The lower end of the throat 7 is partly closed by a plate 14 which may be formed 95 integral with the throat 7 and is provided with a central aperture 15. A sleeve 16 is constructed to slide on to the throat or cylindrical portion 7 and to snugly surround the same so as to be held in engagement 100 therewith by friction. The lower end of the sleeve 16 is partly closed by an inwardly extending flange 17 formed with apertures 18 for the passage of milk or other fluid, and with a central, enlarged opening 19 through which extends the smaller portion 105 of a valve 20. The valve 20 consists of a conical or frusto-conical body, preferably hollow, but which may be otherwise formed and which is positioned for having its base 110 or flat outer end exposed toward the inner flat face of the plate 14. The valve 20 ex-

tends from the said outer or upper end inwardly through the aperture 19 and always presents an inclined wall to the edge of the aperture 19. When the parts are in the up-right position as seen in Fig. 1, and which position is always assumed for purposes of facility of identification of relative locations in this description, unless otherwise specifically stated, the valve is sustained solely by the flange 17 and leaves the aperture 15 open and free for the inflowing of liquid. When, however, the receptacle 1 is tilted to approximately a horizontal position, the inclined wall of the conical valve 2, which is presented to the edge of the aperture 19 enables the valve to slide outward, especially since the outer portion of the valve is heavier than its inner portion. Thus, the valve is caused to take a seat against the plate 14, and the said plate may, therefore, be properly designated as a valve seat. To insure this action with the least possible tilting of the receptacle 1 that would lead to discharge of liquid therefrom, the outer portion of valve 20 is preferably weighted beyond its normal weight by having its base or outermost wall formed of thicker material, preferably of metal, than the other walls. This excess weight can, of course, be secured in many other ways.

In operation, during the course of milking, the streams of milk will strike the walls of the funnel 6 and descend through the strainers and through the aperture 15 down on top of the larger end of valve 20, and falling therefrom will descend through the apertures 18 into the receptacle. Assuming that an accident occurs, causing the bucket or container 1 to be thrown to one side, completely or partly filled, it will be noted that just as quickly as the bucket turns over on its side or assumes an appreciable inclination in that direction, the valve 20 will slide on its inclined wall against the edge of aperture 19 and be caused to rest by gravity with its outer or valve face engaging the valve seat 14, and thus closing the aperture 15 against accidental discharge of liquid from the container. When the bucket is picked up again and set in its upright position, the valve 20 will naturally adjust itself to its normal position. The inclination of the conical walls of valve 20 and their length should be such that the lowest point of the valve face or base of the valve 20 may rest in the angle formed between the inner edge of throat 7 and the adjacent portion of the wall of sleeve 16, with the inner portion of the valve resting against and extending inwardly beyond the edge of the aperture 19, when the parts are tilted as when the bucket is lying on its side.

The sleeve 16 is merely slid upon the throat portion 7 and while held frictionally in place during use, may be easily manually

withdrawn so that the valve 20 may be taken out for purposes of cleansing the parts, and the parts can be as easily re-assembled as they were removed. The cap 11, annulus 9, and filtering screens carried or engaged thereby may also be readily manually removed.

It is apparent, of course, that if the container 1 were overturned or thrown to one side, and the cover or closure 2 should accidentally become dislocated or removed from the container, the valve of the valve 20, and its co-operating parts will be lost. It is, therefore, desirable to provide some efficient, easily and quickly operated means for locking said closure against such dislocation. To this end, and to the further end of preventing the said locking means from interfering with the ready removal of the closure when desired, the receptacle 1 is provided with ears 21, 21, fixed to the opposite sides of the receptacle and each provided, as best seen in Figs. 3 and 4, with an elongated slot 22. While the slot is shown as the ordinary straight slot, it may be otherwise formed as hereinafter mentioned. A bail 23 has its end portions engaging the slots of said ears, each of the said end portions consisting of a horizontal part 24 and a hook portion 25. The horizontal part 24, in each instance, extends through the slot 22, so that the hook 25 will be at the outside of the ear and the body portion of the bail 23 at the inside thereof. Each of the ears 21 outstands from the bead 4 a distance sufficient to accommodate the bail 23 between the bead and ear, and the horizontal portion 24 in each instance is of sufficient length to extend from the ear an appreciable distance beyond the bead 4, whereby the horizontal portion 24 may be caused to overlie the flange 3, as clearly seen in full lines in Figs. 1, 2 and 4. The bail 23 is made of spring material, so that when the horizontal parts 24 thus overhang the flange 3, the bail will actually clamp the inclined walls of the closure 2 and the bail may be swung from its raised position as seen in Fig. 1 to its horizontal position as seen in Fig. 2 and in dotted lines in Fig. 3, without appreciably varying this gripping relation, and while retaining the flange 3 firmly held by the horizontal portion 24, so that the closure 2 cannot accidentally be removed. When it is desired, however, to remove the closure 2, the bail 23 being in the upright position seen in Fig. 1, has its ends moved apart so that the horizontal portions 24 move outward through the respective ears 21 until the bail proper strikes said ears, and then the bail is pressed down until its ends arrive at the lower ends of the slots 22. The bail is then swung to a horizontal position, as indicated in dotted lines in Figs. 3 and 4. The closure 2 is thus freed from engage-

ment of the bail and may be readily withdrawn from the container. When the closure 2 is returned to the container, it is only necessary to swing the bail to its upright position and draw upwardly on the bail until the ends of the bail are moved to the upper ends of the slots 22 when the ends of the bail will spring inwardly to the position overhanging the flange 4.

10 In order to lock the ends of the bail 23 in the position overhanging a part of the closure 2, and also to lock the bail in the released position seen in dotted lines in Fig. 4, an obstruction is provided in the length of 15 each of the end portions 24 such, for example, as a flattened, enlarged portion 24' of greater diameter than the width of the slot 22 and designed, whenever the bail 23 is in its horizontal position, to engage the respective ear 21 at the edges of the slot 22 and to thereby retain the respective end portion 24 against longitudinal reciprocation. It will be noted that the enlargement 24' is of a thickness less than the diameter of the rod 25 forming bail 23, and, therefore, when the enlargement 24' is presented edgewise to the respective slot 22, the enlargement may pass readily through the slot. Thus when the bail is in its uppermost position and swung 30 to a horizontal plane, its ends will be effectively locked against being moved from a position overhanging the flange 3. On the other hand, by springing the lower end portions of bail 23 outward, when the bail is in 35 its upright position, and thus moving the enlargement 24' out through the slot 22, and then swinging the bail 23 to a horizontal position, the bail will be effectively locked out of engagement with the flange 3. This 40 will be true whether the bail 23 is moved to the lower end of the slot 22 or not, and the lowering of the bail in the slots 22 need not occur unless especially desired, and is provided merely as a means of facility in getting the bail entirely out of the way.

In Figs. 6, 7 and 8 is illustrated a slightly modified embodiment in the provision of a globular enlargement 24'' for the horizontal portion 24 of bail 23. In the form seen in Fig. 5, enlargement 24' is preferably formed of the material of the bail stamped to enlarged flattened condition, but in the form seen in Fig. 8, the enlargement 24'' is preferably produced by the casting of the ball 55 onto the horizontal portion 24. The operation of the structure seen in Figs. 6, 7 and 8 is the same as that just above described, except that the ball 24'' is passed through an enlargement 22'' in the slot 22' of the ear 50 21' instead of being capable of being passed through the slot at any point. In this structure the ball 24'' will hold the bail in its

locking position or in the unlocked position, according to its location at one or the other side of the ear 21', and this result is secured 65 only when the horizontal portion 24 is either at one end or the other of the slot 22'.

This application is a continuation in part of my Patent No. 1,217,564, granted February 27, 1917.

What I claim is:—

1. In a device of the class described, the combination with a container and a closure therefor, of a bail for the container, and ears on the container for supporting the bail, 75 said bail having out-turned ends and the ears having restricted openings therein receiving the ends of the bail, each end of the bail having an enlargement adapted, when turned to a predetermined position, to pass through the opening in the adjacent ear in one direction for binding the bail against the closure to hold the latter in place and in the other direction to hold the bail out of engagement with the closure to admit opening thereof.

2. In a device of the class described, the combination with a container and a closure therefor, of a bail for the container, ears on the container through which the end portions of the bail extend, each of the end portions of the bail having a horizontal portion adapted to move longitudinally through the respective ear, and each ear having a slot for accommodating such movement, the slot being formed with an enlargement, and an enlargement fixed to each of the horizontal portions of the end portions of the bail and of a size for passing through the enlarged portion of the slot but too large to 100 pass through other portions thereof, whereby the bail is adapted to be locked with its end portions either engaging the closure or locked out of engagement therewith.

3. In a device of the class described, the combination with a container and a closure therefor, of a bail for the container, an ear mounted on the container for each end of the bail formed with an aperture for the passage of the end portion of the bail, the bail being 110 formed at each end portion with a horizontal portion adapted to move through the aperture in the ear, the horizontal portion being formed with an enlargement adapted to pass through the aperture when in one position relative thereto and not to pass through the aperture when in other positions.

In testimony whereof I affix my signature in presence of two witnesses.

THOMAS S. CATLIN.
